FOREIGN PATENT DOCUMENTS

GB 2472881 A 2/2011

Primary Examiner — Michael C Stout*Assistant Examiner* — Melvin L Davis(74) *Attorney, Agent, or Firm* — The Roy Gross Law Firm, LLC; Roy Gross(57) **CLAIM**

The ornamental design for divot tool, as shown and described.

DESCRIPTION

FIG. 1 is a perspective view of a divot tool in accordance with the new design;

FIG. 2 is a top view thereof;

FIG. 3 is a bottom view thereof;

FIG. 4 is a right side view thereof;

FIG. 5 is a left side view thereof;

FIG. 6 is a rear view thereof;

FIG. 7 is a front view thereof;

FIG. 8 is a perspective exploded view of a divot tool in accordance with the new design;

FIG. 9 is a top exploded view thereof;

FIG. 10 is a bottom exploded view thereof;

FIG. 11 is a right side exploded view thereof;

FIG. 12 is a left side exploded view thereof;

FIG. 13 is a rear exploded view thereof; and,

FIG. 14 is a front exploded view thereof.

The broken lines showing of the divot tool is for the purpose of illustrating portions of the article that forms no part of the claimed design.
